GRAVE DIGGER AND EXCAVATOR

Edith Dean Tyler and George A. Knox,
Watertown, N. Y.

Application June 5, 1939, Serial No. 277,419

3 Claims. (Cl. 255—21)

Our invention relates generally to ground excavating apparatus and particularly to a grave digging device, and an important object of our invention is to provide a device of this character which eliminates manual labor in the digging of graves, thereby making it feasible to dig graves in any weather, at a minimum of cost, and with greater efficiency, and obtain neater and more uniform results than are usually obtained by manual labor.

Other important objects and advantages of our invention will be apparent from a reading of the following description taken in connection with the drawings, wherein for purposes of illustration we have shown a preferred embodiment of our invention.

In the drawings:

Figure 1 is a general front or rear elevational view of the embodiment showing the same mounted in connection with a tractor.

Figure 2 is a top plan view of Figure 1.

Figure 3 is an enlarged transverse vertical sectional view taken through Figure 1 approximately on the line 3—3 and looking toward the right in the direction of the arrows.

Figure 4 is an enlarged horizontal sectional view taken through the upper part of the auger per se above the chute.

Figure 5 is a perspective view of one of the cutters.

Referring in detail to the drawings, the numeral 5 generally designates a fragmentary portion of a tractor, preferably of the caterpillar type which involves the caterpillar or similar tractor element 8 one of the rotors of which has the outboardly extending axle or shaft 7 which in accordance with the present invention is provided with a pinion 8 which is in mesh with another pinion 9 which is mounted on a stub shaft 10 secured in journal brackets 11, 12 to one side of a rigid bracket 13, this bracket involving a pivot 14 on which is pivoted the ear 15 on the inboard end of the heavy channel arm which is generally designated 16. A rotary shaft 17 is carried by bearings 18, 19 at the inboard and outboard ends of the inner side of the web of the channel bar 16, the depressed end of the shaft having a universal connection 20 with the projecting end of the shaft 10 whereby the shaft 17 is driven by the turning of the rotor of the tractor element.

A bracket 21 has a portion 22 angulated with respect to the horizontal and bolted as indicated by the numeral 23 to the lower flange of the channel bar 16 and this bracket has arms 24—25 which are in a substantially horizontal

plane and which closely spacedly surround a groove providing horizontal annulus 26 on the upper end of the generally cylindrical auger housing 27, pins 28 and 29 projecting from the respective arms 24 and 25 at substantially diametrically opposed points, to engage in the groove 20 of the member 26. The extremities of the arms have ears 31 which are traversed by a clamping bolt 32 whereby the bracket 21 is closed around the auger housing.

Another bracket 33 is bolted as indicated by the numeral 34 to the lower side of the lower flange of the channel bar 16 above the bracket 21 and this has a horizontal journal part 35 in which turns a stub shaft 36 on the upper end of which is a gear 37 which is in mesh with the pinion 38 on the upper end of the shaft 17. The lower end of the stub shaft 36 below the bracket 35 has a universal connection 39 with the upper end of the auger shaft 40, the auger shaft having formed thereon or having attached thereto a spiral 41 which is slightly smaller in diameter than the interior diameter of the housing 27 and extends down below the uniform diameter part of the housing and to a point below the flaring lower end portion 42 thereof which is squared to provide for right angularly related walls of double triangle formation to which the respective cutters each typified by the cutter 43 shown in Figure 5 are mounted by means of bolts 44. The upper part of the outboard wall of the uniform diameter portion of the housing 27 is formed with a rectangular opening 45 and under and partially surrounding this opening is the downwardly deflected semi-circular cross section chute 46 which is mounted on the housing to receive and discharge to one side the earth excavated by the auger and carried up through the housing 27 in the course of operation of the device.

Each of the cutters 43 comprises a generally rectangular plate formed with triangular teeth 47 on its lower edge which incline in an axially inward direction from the opposite ends of the cutter to reach a maximum height at the center as indicated by the numeral 48, and the outer sides of the pointed part of these teeth are beveled as indicated by the numeral 49, so that the teeth have a tendency by reason of this formation thereof and by reason of the angulated arrangement thereof to bite into the earth as the auger pulls down in its action of cutting and lifting the earth, so that the corners of the grave pits are square cut automatically by operation of the device. It will be obvious that the size of the

device both as to general bulk and as to the dimensions of the auger and of the cutters 43 may be altered without invention to make the same adequate for digging graves of different sizes.

5 The lower terminal 50 of the auger is beveled as indicated by the numeral 51 and in a diametrically opposite position is a similarly beveled finger finger 52, this arrangement being provided so that the auger bites uniformly into the ground, 10 with the terminals 50 and 53 on a level with or below the lower end of the lowermost points of the cutters 43. It will be observed that the arrangement of the pins 28 and 29 on the arms 24 and 25 in conjunction with the slot 30, and 15 this in conjunction with the universal joint 39, and this further in conjunction with the universal joint 20 and the pivot 14 provides for a continually erect position of the auger in its perpendicular movement into the ground as the device 20 is operated.

Although we have shown and described herein a preferred embodiment of our invention, it is to be definitely understood that we do not desire to limit the application of the invention thereto, 25 and any change or changes may be made in the structure and arrangement of the parts, within the spirit of the invention and the scope of the subjoined claims.

Having described the invention, what is 30 claimed as new is:

1. In combination, a relatively stationary support having a rotary element, a beam inclined away from said support and carrying a longitudinal shaft, means pivoting the depressed end of 35 said beam on said support adjacent said rotary element, first universal means operatively connecting the depressed end of said rotary element and said longitudinal shaft, a housing pivotally depending from the elevated end of said beam, 40 a vertical augur mounting in said housing, second universal means operatively connecting the upper end of the augur with the elevated end of said longitudinal shaft.

2. In combination, a relatively stationary support having a rotary element, a beam inclined away from said support and carrying a longitudinal shaft, means pivoting the depressed end of 5 said beam on said support adjacent said rotary element, first universal means operatively connecting the depressed end of said rotary element and said longitudinal shaft, a housing pivotally depending from the elevated end of said beam, a vertical augur mounting in said housing, second universal means operatively connecting the upper end of the augur with the elevated end of 10 said longitudinal shaft, said housing having excavation dimension defining cutters on its lower end arranged to enter the ground with the augur 15 for making the excavation and conveying the earth upwardly through said housing, and means on said housing for discharging the earth excavated.

3. In combination, a relatively stationary support having a rotary element, a beam inclined away from said support and carrying a longitudinal shaft, means pivoting the depressed end of 20 said beam on said support adjacent said rotary element, first universal means operatively connecting the depressed end of said rotary element and said longitudinal shaft, a housing pivotally depending from the elevated end of said beam, a vertical augur mounting in said housing, second universal means operatively connecting the upper end of the augur with the elevated end of 25 said longitudinal shaft, said housing having excavation dimension defining cutters on its lower end arranged to enter the ground with the augur 30 for making the excavation and conveying the earth upwardly through said housing, and means on said housing for discharging the earth excavated, said cutters each comprising inwardly beveled teeth, some of said teeth having their lower end elevated in position with respect to the 35 lower end of others of the teeth.

EDITH DEAN TYLER.
GEORGE A. KNOX.
